UNITED STATES PATENT OFFICE.

IVERT LARSEN, OF CHICAGO, ILLINOIS, ASSIGNOR TO THE CHICAGO HANDLE BAR COMPANY, OF SAME PLACE.

DESIGN FOR A HANDLE-BAR MEMBER.

SPECIFICATION forming part of Design No. 33,025, dated July 31, 1900.

Application filed December 8, 1899. Serial No. 739,723. Term of patent 7 years.

To all whom it may concern:

Be it known that I, IVERT LARSEN, a citizen of the United States, residing at Chicago, county of Cook, and State of Illinois, have invented and produced a new and original Design for a Handle-Bar Member, of which the following is a specification, reference being had to the accompanying drawings, forming a part thereof, in which—

10 Figure 1 is an elevation showing what for convenience may be called the "face" of the design. Fig. 2 is an elevation showing a side view of the design, and Fig. 3 is an elevation showing the rearward view of the design.

15 The novel features of this design relate to the conformation of the head or inner end of the bar. The head A of the bar is flattened, so as to present a front and rear face, (shown, respectively, in Figs. 1 and 3,) and has a round

20 aperture, as shown, opening through the flat faces. The extreme end of the head is curved to arch form and presents a smooth surface from the front face of the design backwardly for a distance of somewhat more than half of

25 the thickness of the flattened head. Between this smooth curved surface and the rearward

face of the design there is a flange taking the form of the segment of a gear, as shown at B, the plane of which is parallel with the longitudinal axis of the inner end of the bar. 30

The features thus far described form the essential parts of the design and are shown in solid lines.

The minor or non-essential parts of the design (shown in dotted lines) comprise the 35 contracted shank C, uniting a head A with the body portion of the bar D, and a series of serrations in the rearward face of the head and encircling and radiating from the aperture therethrough.

Having described my invention, what I claim as new, and desire to secure by Letters Patent, is—

The design for a handle-bar member, as herein shown and described.

In testimony whereof I have signed my name to this specification in the presence of two subscribing witnesses.

IVERT LARSEN.
